UNITED STATES PATENT OFFICE.

JOSEPH G. MERRIAM, OF MERIDEN, CONNECTICUT, ASSIGNOR TO J. G. MERRIAM COMPANY, OF MERIDEN, CONNECTICUT, A FIRM COMPOSED OF J. G. MERRIAM, A. W. FOSTER, AND E. A. MERRIAM.

TURNTABLE FOR PHONOGRAHS.

1,347,113.

Specification of Letters Patent. Patented July 20, 1920.

Application filed June 22, 1917. Serial No. 176,256.

To all whom it may concern:

Be it known that I, JOSEPH G. MERRIAM, a citizen of the United States, residing in Meriden, county of New Haven, and State 5 of Connecticut, have invented a certain new and useful Turntable for Phonographs, of which the following is a specification.

This invention is a turn-table for phonographs and relates to improvements in such 10 devices, with a view to overcoming defects well known to those skilled in the art.

Turn-tables, as now employed, are generally made in the form of gray iron castings, and, as they embody a comparatively thin, 15 broad expanse, they are usually taken from the flask in a slightly warped condition, due to unequal shrinkage during the cooling of the molten metal. It is the practice to thereafter place the turn-table face down 20 upon a true surface and peen the same, *i. e.*, hammer the back of the casting, to bring all parts of the face thereof into engagement with said true surface. This peening operation is generally carried on around the 25 edge or circumference of the casting, and, in order that said casting will maintain the position into which it is peened, the circumference thereof is generally provided with a downwardly extending flange and it is on 30 this flange that the hammering is received.

Experience has shown that, when a turn-table is peened in the manner described, the hammer leaves marks in the circumferential flange of the casting which render the same 35 uneven, thereby requiring that the flange be trimmed or machined in order not to interfere with the operation of the phonograph brake mechanism or leave an uneven surface which might cut the fingers of a person in- 40 advertently touching the same when applying a record to the turn-table. When the flange is machined as described, it is necessary to frequently cut sufficient metal there- 45 from, before the hammer marks are re- moved, to preclude said flange from carrying out its functions. Thus, after a casting has been properly peened, the flange, after 50 being trimmed, may be of insufficient body to hold the casting in the true form into 55 which it has been forced during the peening operation, with the result that, as the flange is cut away, the casting will assume its original, warped condition.

Another well known disadvantage in turn-table construction is the extreme weight 55 or ponderosity thereof. In operating a heavy turn-table, it is necessary to employ a motor equal to the task, and thus, in many cases, large, cumbersome motors are used where, if the turn-table were lighter, a much 60 smaller motor might be availed of. This not only adds to the weight of the machine, but materially increases the cost thereof. Some attempts have been made to overcome this difficulty by counter boring holes in the 65 pattern, but this operation does not reduce the turn-table to the required weight, and is laborious and costly.

With the foregoing considerations in mind, the object of the present invention is 70 to provide a turn-table embodying the usual cast plate with the circumferential flange, but having associated therewith an additional flange positioned interior of the circumferential flange, which additional flange 75 is adapted to receive the blows transmitted during the peening operation, and provides a sufficient mass of metal to maintain the casting in the position into which it is forced during this operation. Said additional 80 flange may also serve as a braking flange when employed with machines adapted to brake the turn-table from the under side thereof.

A further object of the invention is to 85 form the body of the turn-table from a plu- rality of bands or ribs with intervening inter- stices, which bands or ribs are so placed that, when the turn-table is cast from its center, the flow of molten metal to all parts 90 of the mold may be speedily accomplished because of the particular placement of the ribs and their intersections, whereby blow- holes or other defects in the casting will be obviated. In this manner, a very light, yet 95 strong and rigid, turn-table is produced, with a great saving of metal and the ob- viating of the necessity of using relatively high power motors for the operation of the phonograph with which the turn-table is 100 associated.

Features of the invention, other than those specified, as well as the advantages thereof, will be apparent from the herein- 105 after detailed description taken in conjunc- tion with the accompanying drawings.

In the accompanying drawings, I have illustrated different practical embodiments of the invention, but the constructions therein shown are to be understood as illustrative, only, and not as defining the limits of the invention.

Figure 1 is an underneath plan of the preferred form of turn-table constructed in accordance with the present invention.

10 Fig. 2 is a section on the line 2—2 thereof.

Fig. 3 is a view similar to that of Fig. 1, but showing a slightly modified form of the invention, and

15 Fig. 4 is a section on line 4—4 of Fig. 3.

Referring to the drawings, and more particularly Figs. 1 and 2, A designates a turn-table embodying a relatively thin plate C of substantially flat, circular configuration, provided at the center of its under side with 20 a hub B. The hub is apertured, as usual, to receive the operating shaft of a phonograph. Plate C is provided at its periphery with a depending, circumferential flange c, and immediately inside of said flange with a second, 25 lower and broader flange c', as shown in Fig. 2. Thus, plate C is bordered by flange c and is thickened immediately interior of said flange by virtue of flange c'. Experiment has shown that flange c' is of considerable practical importance, since it allows 30 of the peening operation, subsequently to the casting of the plate, on the face of the flange, which is normally concealed by the deeper flange c. Moreover, said flange c' 35 may be trimmed, after the peening operation, without cutting flange c or decreasing the mass of metal initially cast therein. Thus, after the plate has been trued up, and the face of flange c' trimmed, if necessary, 40 there still remains ample and sufficient metal in the flanges c and c' to assure rigidity of the edge of the plate and preclude the same from warping or returning to its initial, warped condition, in which it may have been 45 subsequent to the casting operation and before the peening operation.

Another advantage flowing from the employment of flange c' is that, when in use, the face of the flange furnishes a smooth 50 braking surface for such machines as brake upwardly, or this surface may coöperate with the adjacent vertical edge of flange c to form a braking angle for such machines as brake in this manner. The salient feature, however, in the employment of the flange c' is that the peripheral or circumferential portion of the plate is extremely 55 rigid and will run true, said flange serving to withstand any tendency of the plate to warp.

The incorporation of the flange, as described, in turn-tables as now constructed, will greatly increase the durability thereof, as well as obviate manufacturing difficulties, 65 but, in practising the present invention, I

prefer to make the body of the plate of skeletonized character, which, in the preferred form, is of a sort of lattice-work formation, embodying intersecting bands forming diamond-shaped interstices. The arrangement of the bands may vary, but a very practical form of construction is shown in Fig. 1, where certain of the bands d extend radially from the central portion of the plate to the flange c', while other of the bands d' extend obliquely from bands d so as to intersect one another and terminate at the flange c'. This formation is one of the most satisfactory from a manufacturing standpoint and does not possess merely 70 esthetic attributes. It particularly recommends itself to the casting art, it being manifest that a construction of the character shown may be readily molded and thereafter cast from its center with the best results. This is for the reason that there are no "blind alleys" into which the molten metal passes. The metal flows from the center of the mold in a general outward direction at all times, all of the passages through 75 the mold feeding outwardly and communicating either with the center of the mold or one of the radial or substantially radial channels. There is no back flow of metal whatsoever, and any residual air which may be in the mold will be forced through the crack usually provided between the flask sections at the outer edges of molds, and will not become entrained in blind alleys and cause blow-holes.

The turn-table shown in Fig. 3 is very similar in construction to that of Fig. 1, embodying a plate C', a hub B', and flanges f and f', corresponding to the flanges c and c'. The main difference between the two 105 structures is that, while the outer edge of the plate in Figs. 1 and 2 is shown as perpendicular to the face of the plate, the outer edge of the structure shown in Figs. 3 and 4 is rounded over, and the bands e, which correspond to the radial bands d, are curved instead of straight. Furthermore, the bands e', which correspond to the bands d', are also curved longitudinally to harmonize 110 with the curvature of the bands e. In the construction of Figs. 3 and 4, the interstices e², which correspond to the interstices d² of the preferred construction, are also substantially diamond-shaped. However, between each two adjacent bands e, which are curved in opposite directions, as shown, for the purpose of dividing the plate radially 115 into sector-shaped motifs, the interstices e³ are made substantially square or rhomboidal for the purpose of obviating the formation 120 of blind alleys in the mold or passages therein through which a retrograde movement of the metal to fill the same would be required. In the modified construction, the flow of the metal during the casting operation is free 125 130

and uninterrupted, blind alleys are absent, and blow-holes are avoided, while the resulting structure is light and rigid.

A turn-table constructed in accordance with either embodiment of the invention described has the advantage of being extremely light, yet very rigid, and, when provided with the double flanges *c* and *c'*, is so constituted that warping will not result, 10 since the peripheral portion of the turn-table is in the form of a rigid rim spaced from the hub by an open-work portion formed from diagonal bands. This will give maximum rigidity with a minimum 15 tendency to warp during the casting operation as well as during subsequent use. The placement of the bands is such that the plate will not even have a tendency to warp, though, if it should, the rigid rim will absolutely preclude such deflection.

In casting the foregoing structures, I prefer to use the usual flask, common to the art of casting, but, in conjunction therewith, I employ a match-plate and position the pattern on the match-plate, thereafter completing the molding and subsequently casting in the usual manner. So far as I am aware, I am the first to ever cast a turn-table through the use of a match-plate fixed 25 to produce the desired form of the turn-table to give the desired weight through the use of a perforated pattern fastened to the back of the plate. When the turn-table is cast as described, the tendency of the casting to warp while solidifying is minimized. Notwithstanding the fact that match-plates 30

are known to the casting art generally, they have never been employed in this manner in the production of phonograph turn-tables, the method of producing such devices being 40 of a less efficient nature. Experiment has shown that the old and well known methods heretofore employed are far surpassed by the use of a match-plate as described, both in efficiency and in the results achieved. 45

Having thus fully described the invention, what I claim as new, and desire to secure by Letters Patent, is:

1. A turn-table for phonographs embodying a relatively thin, circular, cast plate 50 provided with a centrally disposed hub and having a relatively deep, narrow, faced flange depending from the outer circumference thereof, and a peening flange of less depth but greater width than the face of the circumferential flange also depending from the under side of the plate in a position directly adjacent the circumferential flange.

2. A turn-table for phonographs embodying a relatively thin, circular, cast plate provided with a centrally disposed hub and having a stepped flange depending from the circumference thereof, with the deepest step of said flange adjacent the circumference of the plate, the lower and inner step 60 of the flange being relatively broad to provide a peening surface, and a deeper or outer step thereof being relatively narrow. 65

In testimony whereof I have signed my name to this specification.

JOSEPH G. MERRIAM.
